UNITED STATES PATENT OFFICE.

GEORGE W. NUSBAUM, OF TAKOMA PARK, MARYLAND.

PERCUSSION FIRING MECHANISM.

1,415,044.

Specification of Letters Patent. Patented May 9, 1922.

Application filed March 18, 1920. Serial No. 267,004.

To all whom it may concern:

Be it known that I, GEORGE W. NUSBAUM, a citizen of the United States, residing at Takoma Park, Maryland, have invented new 5 and useful Improvements in Percussion Firing Mechanism, of which the following is a specification.

This invention relates to firing mechanism for ordnance and more particularly to the 10 percussion type adapted to be associated with the breech mechanism of relatively large caliber guns.

One of the objects of the present invention is to provide a firing mechanism of the above 15 general character which will be safe, reliable, and efficient at all times.

A further object is to provide a practical mechanism of the above character in which straight electrical firing may be done 20 through the platinum breech in the primer or by percussion or by lanyard pull off as desired.

A further object is to provide a mechanism of the last above mentioned character 25 with certain automatically operating safety features adapted to prevent premature explosion.

A further object is to provide a simple mechanism having relatively few parts 30 which may be inexpensively manufactured and in which all parts are so positioned and arranged as to insure ease and readiness of operation at all times.

A further object is to provide a portable 35 percussion firing mechanism applicable to all calibers of guns using pull off firing lanyard.

Other objects will be in part obvious and in part hereinafter pointed out in connection 40 with the following detail description of the accompanying sheets of drawing. In these drawings there is shown one of various possible embodiments of the invention and similar reference characters denote corresponding parts in the several views.

Figure 1 is a rear side elevation showing the breech of a gun, the carrier and the firing mechanism mounted thereon.

Figure 2 is a longitudinal sectional elevation 50 through the firing mechanism.

Figure 3 is a plan view of the part shown in Figure 1.

Figure 4 is a detail view of the mechanism in cocked position, and,

Figure 5 is a similar view of the parts in

firing position immediately before their restoration to normal.

Referring now to the drawings in detail and more particularly to Figure 1, 10 denotes the rear end of a gun, preferably of 60 relatively large caliber, to the rear under side of which at point 11 is pivotally mounted an L-shaped carrier member 12 which is adapted to be swung upwardly into place when the breech block is closed in the usual 65 manner. The upper end of the carrier 12 is provided with a percussion firing lock 13. As this is of well-known construction it is believed to be unnecessary to describe it in detail, it being sufficient to state that a hammer 14 is pivotally mounted on member 17 and held in the position shown by means of a powerful firing spring engaging the opposite end 16 of the hammer and concealed 70 within the lock casing 13. Mounted upon a 75 suitable lug 17 and adapted to turn about a pivot 18 is the hammer cocking lever 20 provided with a latch for engaging the hammer 14 whereby as this cocking lever swings relatively downwards in the direction of the 80 arrow about the pivot 18 the hammer 14 will be raised against the action of the firing spring until released by further downward movement of the cocking lever, whereupon it returns to normal position and strikes the 85 end of the primer as shown more clearly in Figure 2. These parts being of well-known construction and forming no special part of the present invention except in so far as the 90 elements enter broadly into certain combinations, a further description thereof is believed to be unnecessary, as the present invention deals more particularly with the 95 actuating mechanism for moving the cocking lever.

This mechanism, which is more clearly shown in Figures 2, 4 and 5, comprises a plunger 22 having a slotted connection 23 with an actuating pivot 24 on the cocking lever. It is also pivotally connected at 25 100 with the body portion 26 of the plunger which is provided with a head 27 adapted to reciprocate within the sleeve 28. This sleeve is also concentrically disposed with respect to a stationary cylindrical casing 30 105 mounted upon the carrier 12 in any desired manner. A spring 31 surrounds the plunger 26 and coacts between the head 27 and the end wall of the sleeve 28 whereby as the parts are moved from the normal position 110

shown in Figure 2 to the cocked position shown in Figure 4 this spring 31 will be compressed in the manner shown.

Immediately beneath the casing 30 is a second spring 32 acting between a lug 33 on the casing and a lug 34 on the sleeve 28. This spring is also compressed during the cocking operation or when handle 35 is manually pulled down from the position shown 10 in Figure 1. The parts are held in the cocked position shown in Figure 4 by means of a latch 36 pivoted at 37 on the casing 30. This latch is provided with an extension 38 at the opposite end adapted to be engaged 15 by a lug 40 carried by the plunger 26 immediately after firing, thereby to raise the latch 36 from its engagement with the end of the sleeve 28 and allow the parts to return to normal position under the action of 20 spring 32. A safety sear 41 is pivotally mounted at 42 in the plunger head 27 and normally urged outwardly by small spring 43. The plunger 26 is provided with a notch 44 adapted to be engaged by the end of a 25 solenoid core 45 which is actuated by the energizing of solenoid 46 from any convenient source of electrical energy. This releasing solenoid is usually operative by 125 volts, this high voltage being brought into 30 play by a relay switch which in turn is to be operated by the regular director scope firing key. The operation of this mechanism is as follows:—

The firing plunger 26 is cocked manually 35 by means of the handle 35 which preferably screws into the spring sleeve 28. When this sleeve 28 is drawn downwardly about two inches the latch 36 engages it and holds the firing spring 31 compressed until ready for 40 firing. The solenoid 46 operates the end of the solenoid core 45, which is really a sear, whereupon the plunger is released and by means of the connecting link 22 or the forward part of the plunger the hammer cocking 45 lever 20 of the firing lock is rotated sufficiently to release the hammer and fire the gun by percussion. When the plunger 26 approaches the end of its travel towards the bottom, Figure 5, the plunger 26 having 50 moved from the position shown in Figure 4 to that shown in Figure 5 under the action of spring 31 then the lug 40 engages the projecting end 38 of the latch or lever 36 and presses it downwardly thereby releasing the 55 cocking spring sleeve 28 which is immediately returned to its initial position by the compressed spring 32. The connecting rod or link 22 is provided with a slot 23 which permits the retraction of the firing lock 60 wedge for repriming.

In order to insure the proper functioning of the device and prevent premature firing of the gun, the safety sear 41 is introduced. In case the sear 45 with the solenoid fails to 65 engage the firing plunger 26 this safety sear

41 engages the housing 30 and prevents cocking the mechanisms. If the plunger comes to rest in its proper position, the sear in the solenoid will prevent the plunger from following the sleeve back while cocking the 70 mechanism. The safety sear 41 will be shoved out of engagement with the housing 30 by movement of the sleeve 28.

It is, of course, to be understood that this mechanism is intended to be housed by a 75 suitable cover 51 shown in Figure 1 and an electric cable 47 is intended to be encased in armor to prevent short circuits through abrasion of the insulation. The breech end of the cable is preferably fitted with a water 80 tight terminal 48.

When desired the percussion mechanism may be fixed by means of a lanyard 50 indicated in dotted lines, Figure 1, and attached to the upper end of the cocking lever 20. 85

From the above description it will be seen that the present invention provides a simple, practical and reliable percussion firing mechanism particularly adapted for use on relatively large guns. The entire mechanism 90 is so compact and self-contained, however, that it may be easily mounted, or interchanged from one gun to another regardless of the caliber, it being only necessary to substitute a longer or shorter link for the 95 member 22 as may be necessary or desired.

Without further analysis, the foregoing will so fully reveal the gist of this invention that others can, by applying current knowledge, readily adapt it for various applications without omitting certain features that, from the standpoint of the prior art, fairly constitute essential characteristics of the generic or specific aspects of this invention, and therefore such adaptations 100 should, and are intended to be comprehended within the meaning and range of equivalency of the following claim.

What I claim is:—

1. In combination with a firing lock, a 110 plunger adapted to be connected therewith, a movable member associated with the plunger, a spring connecting said parts and adapted to be manually compressed when the firing mechanism is cocked, electrically 115 operated means co-acting with one of said parts adapted to release the same and permit said spring to return to its normal tension thereby to actuate the firing lock and automatic means for restoring said parts to 120 normal position.

2. In combination with a firing lock, a plunger adapted to be connected therewith, a movable member associated with the plunger, a spring connecting said parts and 125 adapted to be manually compressed when the firing mechanism is cocked, electrically operated means co-acting with one of said parts adapted to release the same and permit said spring to return to its normal ten- 130

sion thereby to actuate the firing lock, and a return spring associated with the movable parts for restoring the same to normal position.

5 3. In combination with a firing lock, a plunger adapted to be connected therewith, a movable member associated with the plunger, a spring connecting said parts and adapted to be manually compressed when the firing mechanism is cocked, electrically operated means co-acting with one of said parts adapted to release the same and permit said spring to return to its normal tension thereby to actuate the firing lock, and 10 a return spring associated with the movable parts for restoring the same to normal position.

4. In combination with a firing lock, a plunger adapted to be connected therewith, 20 a movable member associated with the plunger, a spring connecting said parts and adapted to be manually compressed when the firing mechanism is cocked, electrically operated means co-acting with one of said parts, adapted to release the same and permit said spring to return to its normal tension thereby to actuate the firing lock, and a return spring associated with the movable parts for restoring the same to normal position, 25 said return spring being compressed on the manual cocking of the mechanism and automatically released by the restoration of said firing spring to its normal tension.

30 5. In a firing mechanism, the combination of a firing lock including a cocking lever, a plunger, a member associated with said plunger adapted to be manually moved to cock the firing mechanism, a spring acting between said member and the plunger adapted to be compressed during the cocking, means engaging one of said parts adapted to release the same from cocking position whereby as said spring returns to its normal tension it will actuate said plunger in a 35 direction away from the cocking lever to exert a pull thereon, and a return spring associated with the firing mechanism adapted to restore the parts to normal position.

40 6. In a firing mechanism, the combination of a firing lock including a cocking lever, a plunger, a member associated with said plunger adapted to be manually moved to cock the firing mechanism, a spring acting between said member and the plunger adapted to be compressed during the cocking, means engaging one of said parts adapted to release the same from cocking position whereby as said spring returns to its 45 normal tension it will actuate said plunger in a direction away from the cocking lever to exert a pull thereon and a return spring as-

sociated with the firing mechanism adapted to restore the parts to normal position, said return spring being compressed on the manual cocking of the firing mechanism and automatically released by the movement of said plunger.

5 7. In a percussion firing lock including a cocking lever, a plunger connected with said cocking lever, a sleeve surrounding said plunger, a spring interposed between the plunger head and the sleeve wall adapted to be compressed on the manual cocking of the gun by relative movement of the sleeve, 70 a latch adapted to hold said sleeve in cocked position, a sear for retaining and releasing said plunger, means for releasing said sear and means actuated by the plunger for releasing said sleeve.

8. In a firing mechanism the combination with the firing lock of a spring operated cocking plunger, a sleeve surrounding said plunger, a spring interposed between the sleeve and plunger head adapted to be compressed on manually setting and manually cocking the gun by relative movement of the sleeve, a latch engaging the sleeve, a return spring and a releasing sear connected with the plunger, means for actuating 90 said releasing sear whereby said plunger is moved relatively away from the firing lock to fire the gun and means actuated by said movement adapted to engage the latch to permit said return spring to restore the 95 parts to said normal position.

9. In a firing mechanism the combination with the firing lock of a spring operated cocking plunger, a sleeve surrounding said plunger, a spring interposed between the 100 sleeve and plunger head adapted to be compressed on manually setting and manually cocking the gun by relative movement of the sleeve, a latch engaging the sleeve, a return spring and a releasing sear connected with 105 the plunger, means for actuating said releasing sear whereby said plunger is moved relatively away from the firing lock to fire the gun, means actuated by said movement adapted to engage the latch to permit said 110 return spring to restore the parts to said normal position and safety means associated with said plunger adapted to prevent a cocking of the gun when said firing sear is out of engagement with said plunger.

10. In combination with a firing lock, a plunger, a housing for said plunger, a firing sear adapted to engage said plunger, and safety means adapted to prevent a cocking of the gun when said firing sear is out 115 of engagement with said plunger.

Signed at Washington, District of Columbia, this 31st day of Dec., 1919.

G. W. NUSBAUM.
